UNITED STATES PATENT OFFICE.

VICTOR E. EXTROM AND CHARLES HANCOCK GRUNDY, OF TOMAHAWK, WISCONSIN.

ELECTRIC-LAMP SOCKET.

No. 910,185.

Specification of Letters Patent. Patented Jan. 19, 1909.

Application filed October 9, 1907. Serial No. 396,624.

To all whom it may concern:

Be it known that we, VICTOR E. EXTROM and CHARLES HANCOCK GRUNDY, both citizens of the United States, and residents of 5 Tomahawk, in the county of Lincoln and State of Wisconsin, have invented a new and Improved Electric-Lamp Socket, of which the following is a full, clear, and exact description.

10 The purpose of this invention is to provide novel, simple details of construction for an electric lamp socket, which will serve to control the flow of current to two lamps by the turning movement of a single key, and thus 15 effect the lighting of either one of two lamps, light both lamps simultaneously, or extinguish them together or successively as may be desired.

The invention consists in the novel construction and combination of parts, as is 20 hereinafter described and defined in the appended claims.

Reference is to be had to the accompanying drawings forming a part of this specification, 25 in which similar characters of reference indicate corresponding parts in all the views.

Figure 1 is a perspective view, showing two electric lamps connected by means of the improvement; Fig. 2 is an enlarged partly 30 sectional side view, showing the interior construction of the improved socket, having parts thereof adjusted for cutting off electric connection from two lamps that are directly connected therewith; Fig. 3 is a partly sec- 35 tional side view of the improved socket, showing details therein adjusted for lighting a single lamp; Fig. 4 is a side view of the improved socket, broken away, showing interior parts adjusted for lighting two lamps 40 at the same time, and Fig. 5 is a sectional plan view of the improved socket, substantially on the line 5—5 in Fig. 2.

It has been found of great practical advantage to enable the quick and convenient 45 control of a lamp pendent from a ceiling or on a side bracket, and another lamp on a movable stand, by manipulation of a single key which is carried by a socket on one of the lamps.

50 In carrying into effect the principle of our invention, one embodiment is shown and comprises the following details: A socket body 5 that is mainly cylindrical and may be formed of plate metal to avoid excessive 55 weight, is contracted in diameter at or near its normally lower end, thus producing a hol-

low branch 5^a thereon. At one side of the body 5, a lateral hollow branch 5^b is formed or secured. The body and its branches are lined with insulating material that forms a 60 continuous wall therein.

Within the portions of the lining 6 that extend into the branches 5^a, 5^b, metallic sleeves or linings 7 are inserted. The lining walls 7 are internally threaded and said 65 threads may be indented into the insulating wall 6, these threads being quite coarse to adapt them for the engagement therein of parts that will presently be described.

Upon the upper end of the body 5, a cap 70 piece 5^c is fitted and secured detachably, it having a central opening b therein that permits the insertion of positive and negative electric conductor wires c, c', within the body of the socket. The wires c, c', are in- 75 sulated from each other, and one wire c', is firmly secured at its end upon an upwardly extended strip c², that is on the lining shell 7 which occupies the insulation 6 in the lateral branch 5^b, as shown in Fig. 2. 80

Two resilient metallic strips d, d', are lapped together at their upper ends and secured by suitable means on the insulating wall 6, preferably at a point directly opposite the branch 5^b, and upon the upper ex- 85 tremities of the connected strips d, d' the depending end of the conductor wire c is secured and adapted for transmission of current through said strips from a source of electricity, when a closed circuit is estab- 90 lished, as will hereinafter appear.

A coupling head 8, formed of plate metal or other available material, is provided with a cylindrical shank 8^a at one end, and said shank is exteriorly threaded and screwed 95 into the thread in the metal lining 7 of the branch 5^b, as shown in Fig. 2.

Two insulated conductor wires e, e', are located in the coupling head 8, one wire e, being attached to the wall thereof, while the 100 other wire e', extends through the shank 8^a and terminates in a resilient contact strip e², that is preferably bent laterally as shown in the drawings, to give it V-shape and thus adapt it for resilient action as a contact 105 finger.

The strip d' is bent at d², so as to project it toward the shank 8^a, and then double folded as shown at d³, from which folds a spring contact limb d⁴ depends, and is 110 positioned near to and opposite the resilient terminal of the strip e² on the wire e'. The

conductor strip d is extended downward, and near the lower branch 5^a of the socket body 5 is double folded, producing a spring f' from which extends a contact limb f toward, but below, the lower end of the contact limb d^4 .

A glass electric light bulb 9 , of usual form and terminating at one end in an exteriorly threaded shank 9^a , is screwed into the internal thread formed in the lining wall 7 for the depending branch 5^a , and in the shank and glass guard stem 9^b that projects therefrom into the bulb 9 , two insulated leading-in wires g, g' , are embedded, and at their terminals, which are positioned at the lower end of the guard stem, and ends of a carbon filament 10 are secured in a manner that insures perfect electrical connection therebetween.

20 As shown, one wire g is bent laterally and at its upper end is embedded in the lining wall 7 for the branch 5^a . The remaining wire g' is extended up through the glass shank 9^a , and at the upper end thereof merges into a resilient contact finger h , that is located directly below but not in contact with, the limb f .

It will be understood from the preceding description, and by inspection of the drawings, that the contact limbs d^4 and f are disposed in the same vertical plane substantially at right angles with each other, and out of contact, and furthermore, that said limbs are normally separated slightly from the contact fingers e^2 and h .

A key shaft i is supported transversely in the body 5 and insulation 6 , by journaling its end portions therein at a point which will dispose said shaft between and at an equal distance from the limbs d^4 and f .

40 A flat grip piece or head i' is formed or secured upon the end of the shaft i that projects outside of the body 5 , and upon said shaft in the same vertical plane with the limbs d^4, f , a presser block i^2 is mounted and secured. The presser block i^2 is formed of hard rubber or other non-conductor of electricity and is peripherally rhombus-shaped, the shaft i being passed therethrough near 50 one of the obtuse angles m thereof.

It will be seen in Fig. 2 that when the shaft i is turned so as to locate the obtuse angle m , it is close to, nearest the free ends of the contact limbs d^4, f , the acute angles of 55 the presser block will be removed from said limbs and the latter will remain in normal position or out of contact with either contact finger e^2, h .

As represented in Fig. 1, the improved 60 socket and depending lamp thereon, is hung by the insulated wires c, c' , from an overhead support, such as the ceiling A in a room, and receives current from a suitable source.

65 The coupling head 8 and wires e, e' , that

are shown broken away in Fig. 2, in complete form extend from the socket branch 5^b to a stand lamp 11 of any preferred construction, and as will be understood, both lamps will be extinguished when the key block i^2 is positioned with regard to the contact limbs d^4 and f , as shown in Fig. 2.

In Fig. 3 is shown an adjustment of parts adapted for lighting the pendent lamp that is illustrated in Figs. 1 and 2, and it will be observed that the presser block i^2 is turned so as to press the obtuse angle m thereof and which is furthest from the center of the shaft i , upon the contact limb f , thus depressing said limb and establishing electric contact 80 between it and the contact finger h , which will close the circuit between the lamp mentioned and the feeding wires c, c' , while the circuit for the other lamp remains open.

If it is desired to light both lamps simultaneously, the key shaft i and presser block i^2 thereon are turned as shown in Fig. 4, wherein it will be seen that the acute angles of the presser block that are opposite each other and an equal distance from the axis of the shaft, press upon the contact limbs d^4 and f , so as to enforce their contact respectively with the contact fingers e^2 and h , thus completing an electric circuit between the pendent and stand lamps and the feed wires c, c' . 95

Obviously the current may be cut off from either or both lamps, by turning the key so as to dispose the presser block as shown respectively in Figs. 3 and 2.

It will be evident that the construction 100 may be slightly changed within the scope of the invention, so as to feed the lamps by the wires e, e' , instead of the feed wires c, c' , and support the coupling head 8 on the outer end of a fixed bracket arm that may project 105 from a side wall in a room, the operation being the same in either arrangement of the feed wires.

Having thus described our invention, we claim as new and desire to secure by Letters 110 Patent:

1. In an electric light socket, a hollow body, a hollow branch on one side of the body, a hollow branch on one end of the body, insulated conducting wires in both branches, 115 electric feeding wires held in the socket body, a key rockable in the body, and means controlled by said key adapted for making and breaking circuit between the feeding wires and the conducting wires in either or both 120 branches.

2. In an electric light socket, a hollow metallic body, a hollow metallic branch on one side of the body, a hollow metallic branch on the lower end of said body, an 125 insulating lining in the body and in the branches, conducting wires in the lateral branch, conducting wires in the depending branch, two electric feeding wires held in the body, electric contacts for the wires in the 130

branches, and a rotatable key adapted by adjustment thereof for making or breaking circuit between the feeding wires and the contacts for the wires in either or both branches.

3. In an electric light socket, a mainly cylindrical hollow metallic body, a hollow metallic branch extended laterally from said body, a hollow metallic branch depending from the body, an insulating lining in the body and in the branches, conducting wires in the lateral branch, conducting wires in the depending branch, electric feeding wires entering the upper end of the body, spring contact limbs extended from the feeding wires, contact fingers on certain of the conductor wires, said limbs being disposed near the contact fingers, and a key shaft adapted for rotation in the socket body, and having a rhombus-shaped presser block thereon adapted by partial rotation for pressing the limbs into contact with either or both contact fingers, and also by further rotatable movement breaking the circuit between the feeding wires and either or both conductor wires.

4. In an electric light socket, a hollow socket body, a lateral branch thereon, an extension head in said branch, a depending

branch on the socket body, an electric lamp having a shank securable in said depending branch, conductor wires extended from an electric stand lamp and held in the extension head, electric feeding wires entering the socket body through the upper end thereof, two resilient conductor limbs connected with respective feeding wires, contact fingers on the lamp shank and on the extension head adapted for current transmission, and a key shaft in the socket body rotatable manually, said shaft having a rhombus-shaped presser block eccentrically disposed on the shaft, and adapted by partial rotation for pressing one or both limbs into engagement with respective contact fingers and establishing a circuit in one or both lamps, and by further turning movement break circuit between either or both contact fingers for extinguishment of the respective lamps.

In testimony whereof we have signed our names to this specification in the presence of two subscribing witnesses.

VICTOR E. EXTROM.

CHARLES HANCOCK GRUNDY.
